CARL LESSIG AND CLARENCE J. CARLEY, OF DALTON, NEBRASKA

DESIGN FOR A GAME BOARD

Application filed September 6, 1932. Serial No. 44,758. Term of patent 3½ years.

To all whom it may concern:

Be it known that we, CARL LESSIG and CLARENCE J. CARLEY, citizens of the United States, residing at Dalton, in the county of Cheyenne and State of Nebraska, have invented a new, original, and ornamental Design for Game Boards, of which the following is a specification, reference being had to the accompanying drawing, forming part thereof.

In the drawing:—

Fig. 1 is a plan view of a game board, showing my new design.

Fig. 2 is a cross section through the board, taken on the line 2—2, Fig. 1.

I claim:—

The ornamental design for a game board as shown.

CARL LESSIG.

CLARENCE J. CARLEY.
